UNITED STATES PATENT OFFICE.

EDWARD B. WESTON, OF DAYTON, OHIO.

PACKING CONTAINER.

Application filed January 9, 1922. Serial No. 527,981.

To all whom it may concern:

Be it known that I, EDWARD B. WESTON, a citizen of the United States, and a resident of Dayton, in the county of Montgomery and State of Ohio, have invented certain new and useful Improvements in Packing Containers, of which the following is a full, clear, and exact description, reference being had to the accompanying drawings, 10 forming part of this specification.

My invention relates to means for packing and shipping fragile articles, more particularly eggs and the like, in which the breakage resulting from the ordinary methods of 15 packing is exceedingly large, and my object is to provide a construction in which eggs especially can be effectively packed cheaply and expeditiously with a minimum liability of breakage even under rough treatment, 20 and in which a square carton of cardboard can be employed instead of the oblong wooden box so generally in use, of substantially the same cubical contents.

With my invention, in addition to perfect 25 support and protection of the fragile goods from contact with each other, the ability to make use of a square outside container for shipment is a marked advantage in itself, inasmuch as square packages are better 30 adapted for packing space and for the same weight of goods an oblong package has for one end farther to drop if carelessly handled and the liability to damage of the contents is consequently greater with oblong packages than with square.

My invention consists of that novel construction of paper partitions and supporting and protecting sections to be hereinafter particularly pointed out and claimed, in which 40 the above results are effectively attained.

In the drawings,

Figure 1 is a perspective view of my improved container, with one outside wall removed and the carton partly packed.

Figure 2 is a perspective view of one of the corrugated sheets.

Figure 3 is a similar view of one of the perforated partitions.

Figure 4 is a plan view of the superimposed sheets showing the position of the eggs.

The construction for holding the articles (and in the drawings I have selected for illustration an egg carrier) comprises a series 55 of corrugated cardboard sections 1, in which the height of the corrugations is somewhat

more than half the length of the average egg.

These corrugated sheets are each also formed with a series of cup-shaped depressions 2, 2, and 3, 3, on both sides of the sheet, so that each side of each sheet is formed with alternate depressions and raised portions along the sides of each corrugation. In the construction illustrated, which is designed to provide a square package for half a dozen eggs in each row, with six rows, there are consequently formed six depressions, and these depressions are opposite each other so as to provide a receptacle 70 for the egg with the raised portions forming a support, while in the opposite side of the sheet the raised portions are corresponding depressions for the support of the eggs.

These corrugated sheets with the depressions and raised portions are exactly alike, and they are preferably formed by pressure 75 between corrugated rollers in long sheets or strips and then severed for the desired length of individual sheet. As it is intended 80 that the sheets shall be laid on top of each other with the crest of the corrugations contiguous, as will be later described, it follows that one end 4 of each sheet will be severed at the bottom of the corrugation 85 and the other end 5 at the top of its corrugation. When thus cut in length and the sheets are piled on each other, the tops of the corrugations will be contiguous without overlapping of the several sheets, and there 90 will be one half a corrugation for each sheet in excess of the number required.

In connection with these corrugated sheets I also employ division sheets 6. These sheets are flat and provided with holes 7 95 to correspond to the number of articles to be packed. These sheets are used alternately with the corrugated sheets and their special purpose is to prevent the eggs or other articles from shifting towards each other 100 laterally. Just as in the case of the corrugated sheets, the openings in these sheets do not come as close to one end as the other, and there is a blank section 7^a at one end, and in the use of these partitions, as will 105 be seen, the ends of the sheets are reversed alternately as the parts are assembled.

In order to pack the eggs or other articles, I proceed as follows.

A square cardboard container 8 is provided 110 of the inside dimensions to hold snugly the corrugated sheets.

In this container a corrugated sheet is laid, and on top of it one of the partition sheets with the holes in the partition registering with the cup-shape recesses for the 5 eggs. Then a layer of eggs, in the present instance three dozen, is packed in the container, with the eggs on end. Next a second corrugated sheet is placed in the container with the corrugation contiguous. This 10 brings the edges of the two sheets together on one edge and diverging at the other edge. A second perforated sheet is then placed in the container, as before, with the holes registering with the depressions. This brings 15 the blank space of the sheet at the other side. A second layer of eggs is packed. The third corrugated sheet and a partition sheet are deposited as before, and the next layer of eggs packed, with the same method con- 20 tinued until the container is filled.

It will be noticed that with the eggs 9 packed in this way, the eggs are not located on top of each other, but diagonally, and that each intermediate layer overlaps the 25 layers above and below, and that therefore for a given height or thickness of the layers many more layers can be packed. Each egg is perfectly supported at substantially eight points of support, and none of the eggs bears 30 against each other with only the thickness of cardboard between them, as in ordinary packages. They are cushioned on all sides, and the points of the eggs are protected by the peak of the corrugation. More space is 35 taken up in a horizontal plane in the cardboard cushions and the eggs are farther apart than ordinarily. This, however, is compensated for by the overlapping of the layers, so that the cubic contents of the 40 square container for, say, 36 dozen eggs will only slightly exceed the cubic contents of the ordinary container in which the eggs in horizontal layers are much closer together.

Having thus described my invention, what I claim as new and desire to secure by Let- 45 ters Patent, is:—

1. In a device of the character specified, in combination with a container, of a series of similarly corrugated sheets, with alternate depressions and raised portions for each 50 side of the sheet along the sides of each corrugation, and with each alternate sheet reversed.

2. In a device of the character specified, in combination with a container, of a series 55 of similarly corrugated sheets, with alternate depressions and raised portions for each side of the sheet, and with each alternate sheet reversed, and a flat sheet with holes corresponding to the number of depressions 60 interposed between each corrugated sheet.

3. In a device of the character specified, in combination with a container, of a series 65 of similarly corrugated sheets, with alternate depressions and raised portions for each side of the sheet along the sides of each corrugation, and with each alternate sheet reversed, and the crests of the corrugations contiguous.

4. In a device of the character specified, 70 in combination with a container, of a series of similarly corrugated sheets, with alternate depressions and raised portions for each side of the sheet, and with each alternate sheet reversed, and the crests of the corrugations 75 contiguous, and a flat sheet with holes corresponding to the number of depressions interposed between each corrugated sheet.

5. A packing container comprising a plurality of corrugated sheets resting on each 80 other with the crests of the corrugations contiguous and partition sheets with perforations therein interposed between each corrugated sheet.

EDWARD B. WESTON.
